PASTE TUBE CLOSURE

Melanie Guidry, Medina, Tex.

Application December 30, 1938, Serial No. 248,566

6 Claims. (Cl. 221—60)

The present invention relates to closures for paste tubes and has for its primary object to provide an upstanding neck at the upper end of the tube, said neck provided with a screw-threaded bore and a discharge opening, together with a closure for the opening having screw means adapted to swing the closure to one side of the opening and at the same time to raise the closure upon the manipulation of the screw.

10 A further object is to provide a device of this character of simple and practical construction, which is efficient and reliable in performance, relatively inexpensive to manufacture and otherwise well adapted for the purposes for 15 which the same is intended.

Other objects and advantages will be apparent from a reading of the following description in connection with the drawings wherein for purposes of illustration I have shown a preferred 20 embodiment of my invention.

Figure 1 is a fragmentary perspective view of the upper end of the paste tube embodying the present invention.

Figure 2 is a fragmentary front elevational view showing the closure away from the opening in the tube.

Figure 3 is a top plan view.

Figure 4 is a sectional view taken substantially on a line 4—4 of Figure 7.

30 Figure 5 is a top plan view showing the closure in its open position.

Figure 6 is a fragmentary side elevational view.

Figure 7 is a fragmentary vertical sectional view taken substantially on a line 7—7 of Figure 5, and

35 Figure 8 is a side elevational view showing the closure in open position.

Referring now to the drawings in detail, the 40 numeral 5 designates a paste tube of conventional construction having the frustro-conical upper portion 6 terminating in an upstanding neck 7. The neck is of segmental form and includes a pair of upstanding side walls 8 which 45 converge toward one end, the opposite ends of the walls being connected by an upstanding inclined arcuate end wall 9 within which the discharge opening 10 is formed.

The converging end walls 8 terminate in a 50 cylindrical boss 11 having an internally threaded bore 13 opening through the top of the boss and adapted to accommodate a threaded screw 14 which is fixedly secured or formed integral with the closure indicated generally at 16, the outer 55 end of the screw being formed with a winged

head 17 to constitute a hand-grip for manipulating the screw.

The closure 16 includes a flat top portion 18 adapted to overlie the top 15 of the neck, the top of the closure being substantially coextensive with the top of the neck when the former is in its closed position, the outer edge of the top 18 of the closure terminating in a downwardly inclined apron 19 adapted to swing into and out of position with respect to the arcuate end portion 9 of the neck. To the under side of the closure is secured a cork or similar gasket 20, the gasket being coextensive with the under or inner side of the closure and is also provided with an opening through which the screw 14 is inserted.

From the foregoing is will be apparent that upon the manipulation of the winged head 17 that the closure may be swung into and out of position with respect to the opening 10 and during such swinging movement the closure will further be raised or lowered in accordance with the threading or unthreading of the screw 14, as the case may be.

The inclined wall or apron 19 bearing against the inclined end wall 9 of the neck portion will provide a tight seal for the closure over the opening 10 when the screw is threaded home.

It is believed the details of construction and manner of operation of the device will be readily understood from the foregoing without further detailed explanation.

Having thus described the invention, what I claim is:

1. A paste tube closure comprising a neck rising from the tube, said neck being of predetermined cross sectional form and including a side wall having a discharge opening therein and a closure swingably mounted on the neck and including an apron movable relative to the wall into and out of closing position with respect to the opening.

2. A paste tube closure comprising a neck rising from the tube of segmental form and including a pair of side walls converging at one end and an arcuate end wall connecting the other end of said side walls and provided with a discharge opening and a closure swingably mounted on the neck and having a depending apron adapted to cover the opening.

3. A paste tube closure comprising a neck rising from the tube, said neck being of segmental form and including a pair of side walls converging at one end and an arcuate end wall connecting the other end of said side walls and

50

55

provided with a discharge opening, a boss at the converging ends of said side walls and having an internally threaded bore opening through the top of said neck, a screw threaded in said bore and a closure carried by the screw for swinging into and out of position with respect to the opening upon the manipulation of the screw.

4. A paste tube closure comprising a neck rising from the tube, said neck being of segmental form and including a pair of side walls converging at one end and an arcuate end wall connecting the other end of said side walls and provided with a discharge opening, a boss at the converging ends of said side walls and having an internally threaded bore opening through the top of said neck, a screw threaded in said bore and a closure carried by the screw for swinging into and out of position with respect to the opening upon the manipulation of the screw, said closure including an apron adapted to bear against the arcuate end wall of the neck when the closure is in its closed position, said closure and apron being movable vertically during the manipulation of the screw.

5. A paste tube closure comprising a neck rising from the tube, said neck being of segmental form and including a pair of side walls converging at one end and an arcuate end wall connecting the other end of said side walls and

provided with a discharge opening, a boss at the converging ends of said side walls and having an internally threaded bore opening through the top of said neck, a screw threaded in said bore and a closure carried by the screw for swinging into and out of position with respect to the opening upon the manipulation of the screw, said closure including an apron adapted to bear against the arcuate end wall of the neck when the closure is in its closed position, said closure and apron being movable vertically during the manipulation of the screw and manipulating means at the outer end of the screw.

6. A paste tube closure comprising a neck rising from the tube and including a discharge opening, and an internally threaded bore opening through the top of said neck, a screw threaded in said bore and a closure carried by the screw for swinging into and out of position with respect to the opening upon the manipulating of the screw, said closure including an apron adapted to bear against the discharge opening of the neck when the closure is in its closed position, said closure and apron being movable vertically during the manipulation of the screw and manipulating means at the outer end of the screw.

MELANIE GUIDRY.
